UNITED STATES PATENT OFFICE.

WILLIAM T. LANE, OF FOSTORIA, OHIO

GUARD OR FENDER FOR CARS.

No. 841,651.

Specification of Letters Patent.

Patented Jan. 15, 1907.

Application filed October 27, 1906. Serial No. 340,814.

To all whom it may concern:

Be it known that I, WILLIAM T. LANE, residing at Fostoria, in the county of Seneca and State of Ohio, have invented a certain new and useful Improvement in Guards or Fenders for Cars, of which the following is a full, clear, and exact description, reference being had to the accompanying drawings.

My invention relates to guards or fenders for railway-cars, and has for its object to provide a guard or fender of this character that may be applied to cars without the necessity for any change in the parts of the car with which it is to be associated and which shall be simple of construction, but effective in operation, and which, should the fender be subjected to a blow or shock sufficient to break or destroy the same, will not result in derailing the car by reason of the fender striking the rail in front of the wheel to which it is applied.

Generally speaking, my invention consists of the combinations of elements for the purposes specified hereinafter described and claimed.

Referring to the drawings, Figure 1 represents a side elevation of the lower portion of a car having my invention applied thereto. Fig. 2 represents an enlarged perspective view of a wheel and the associated portion of the truck with my invention attached to the latter. Fig. 3 represents a front elevation of the devices shown in the preceding figure, and Fig. 4 a side elevation of the lower end of the fender.

Describing the parts by reference characters, 1 represents a car of ordinary construction having the usual trucks 2, said trucks being represented as of the diamond type, 40 comprising the upper or arch bar 3 and the tie-bar 4, between the end portions of which are fitted the journal-boxes 5 for the wheels 6.

7 denotes the bolts by which the journal-boxes are secured in place between bars 3 and 4. Each of the end wheels of the car is provided with my guard or fender 8. This guard or fender comprises a flange 9; corresponding in curvature to the face of the wheel and carried by a web 10. The flange 50 extends from the top of the wheel to a point adjacent the rail 11, being of sufficient vertical extent to prevent any object from being readily inserted between the top of the same and the adjacent face of the car-wheel. The inner edge 12 of the web which carries this

flange is preferably straight or vertical, and said web has secured thereto the angle-irons 13 and 14, the vertical flanges whereof are riveted to the web, the distance between the horizontal flanges of said angle-irons being 60 equal to the distance between the top of bar 3 and bottom of bar 4. The horizontal flanges of the angle-irons are provided with holes for the reception of the bolts 7, by which the journal-boxes are secured in place, 65 thereby enabling me to apply my guard to the wheel without the necessity for any change in or addition to the regular equipment of the car for the purpose of accommodating the same. 70

The lower end of the fender extends to a point about an inch and a half from the rail 11. The lower portion of the flange 9 is given a slight twist or bend to cause the same to be beveled or inclined from the inner edge 75 toward the outer edge thereof, and to this lower portion of the flange is secured a shoe 15, which is similarly inclined, as indicated more particularly in Figs. 2 and 4, whereby on striking an object there is a tendency to 80 push the same off the track outside of the rail, whereby the car will not pass over the object. As is well known, persons are frequently struck by cars moving at a rate of speed so slow as not to seriously injure the 85 victim; but on account of being thrown under the car between the tracks the life of the person thus struck is destroyed by his encountering some portion of the frame or equipment of the car-body. Under all ordinary conditions a person struck by my fender will, on account of the shape of the lower end of the same and of the shoe 15 be thrown outwardly from the track, so that no further injury will be caused by the passage of the 90 car. 95

The guard is necessarily made of strong material. I prefer to use eight-gage boiler-plate in its construction. This, taken with the shape of the same, provides a fender which 100 will withstand all ordinary shocks or blows to which it may be subjected. It may happen, however, that an unusually heavy obstacle is struck or that a lighter obstacle is struck when the car is moving at a high rate 105 of speed. This would result in breaking the fender loose from its supports or in at least bending the same downwardly into the path of the wheel, thereby rendering the car liable to derailment. To reduce this danger to a 110

minimum, the shoe 15 is made of a casting sufficiently light to break under a shock that will endanger the fender-body and its supporting means. The shoe and the object will probably be thrown from the rail by the impact; and the shoe, being cheap of production, may be replaced at a trifling expense. Should the casting not clear the rail, however, its relatively small size will not necessitate the derailing of the car should the wheel happen to strike the same. To reduce to a minimum the injury to the person struck, the heads of the bolts 16 should be countersunk in the casting, and the lower edge of the shoe should be rounded.

As will be noted, the lower portion of the fender conforms to the curvature of the wheel, thereby bringing the front end of the same and the shoe or casting 15 into close proximity to the wheel. This enables me to carry the shoe or casting 15 at a distance of half or three-quarters of an inch from the rail without any danger of striking the rail should a sharp grade be encountered. Furthermore, owing to the vertical extent of the fender, it is almost impossible for a person falling from the car in front of the wheel to get an arm or leg in the space between the wheel and fender.

I claim—

1. A fender for cars comprising a curved body conforming in curvature to the wheel with which it is to be employed and having at the lower end thereof a frangible shoe, substantially as specified.

2. A fender for cars comprising a curved body adapted to be applied in front of a car-wheel and having at its lower extremity a frangible shoe, said shoe being beveled or inclined from the inner edge toward the outer edge thereof, substantially as specified.

3. A fender for cars comprising a web carrying a flange, said flange conforming in curvature to the wheel with which it is to be employed, and said web carrying attaching means adapted to be applied to the truck, above and below the journal-box of the wheel, substantially as specified.

4. The combination of a truck, a wheel having a journal-box, bolts for securing said journal-box to said truck, and a fender for said wheel having a pair of supporting members spaced apart to receive therebetween the ends of the truck and the journal-box and provided with holes for the reception of said bolts, substantially as specified.

5. The combination of a truck having upper and lower bars or members, a wheel having a journal-box, bolts connecting said journal-box to said bars or members, a wheel 60 guard or fender having a flange projecting in front of the face of the wheel, and means for supporting said guard or fender, said means comprising an upper and a lower angle-iron, the horizontal flanges of which are 65 spaced apart a distance substantially equal to the distance between the top of the upper truck member and the bottom of the lower truck member and having openings for the reception of the bolts by which the journal-box is secured to said members, substantially as specified.

6. A fender for car-wheels comprising a web having a flange projecting laterally therefrom, said flange conforming in curvature to the curvature of the wheel with which it is to be employed, and a pair of angle-irons riveted or otherwise suitably secured to said web, substantially as specified.

7. The combination of a truck having upper and lower bars or members, a wheel having a journal-box, bolts connecting said box to said bars or members, a fender for said wheel comprising a web having a flange projecting laterally therefrom, said flange 75 conforming in curvature to the curvature of the wheel with which it is to be employed, and a pair of angle-irons having their vertical flanges riveted or otherwise suitably secured to said web and their horizontal flanges 80 spaced apart a distance equal to the distance between the top of the upper and the bottom of the lower truck member and having holes for the reception of said bolts, substantially as specified.

8. A guard or fender for car-wheels comprising a heavy sheet-metal web having a laterally-projecting flange conforming in curvature to the curvature of the wheel with which the guard or fender is to be employed, means for supporting said guard or fender with the lower portion thereof a short distance above the rail, and a frangible shoe secured to the lower front end of said fender and having its lower edge projecting below 95 the same, substantially as specified.

In testimony whereof I hereunto affix my signature in the presence of two witnesses.

WILLIAM T. LANE.
